UNITED STATES PATENT OFFICE.

WARREN F. WHEELER, OF STONEHAM, MASSACHUSETTS.

GUTTER SNOW-PLOW.

1,190,832.

Specification of Letters Patent. Patented July 11, 1916.

Application filed February 26, 1915. Serial No. 10,701.

To all whom it may concern:

Be it known that I, WARREN F. WHEELER, a citizen of the United States, and resident of Stoneham, in the county of Middlesex 5 and State of Massachusetts, have invented certain new and useful Improvements in Gutter Snow-Plows, of which the following is a specification.

This invention relates to plows adapted to 10 work beside a sidewalk curb and force snow outwardly therefrom to clear the gutter beside the curb.

The invention has for its object to provide an effective gutter plow adapted to be 15 adjusted to meet various requirements, and of strong and durable construction.

The invention consists in the improvements which I will now proceed to describe and claim.

20 Of the accompanying drawings forming a part of this specification: Figure 1 represents a side view of a snow plow embodying my invention, the scraper hereinafter referred to being raised; Fig. 2 represents a 25 view similar to a portion of Fig. 1, showing the scraper lowered; Fig. 3 represents a section on line 3—3 of Fig. 1; Fig. 4 represents a section on line 4—4 of Fig. 1; Fig. 5 represents a section on line 5—5 of 30 Fig. 2, and a front elevation of parts at the left of said line.

The same reference characters indicate the same or similar parts in all the views.

My improved snow plow comprises a 35 frame which includes an inner runner 12, an outer runner 13, and a superstructure extending above the runners, the whole forming a rigid frame capable of being drawn by a horse, and supporting the movable 40 parts hereinafter described.

Since the construction of the superstructure may be variously modified it need not be described in detail further than by stating that it preferably includes front and 45 rear uprights 14, 15, at opposite ends of the outer runner, and formed of metal integral with said runner, horizontal frame members including a longitudinal member 16 bolted to the upper ends of said uprights, 50 transverse members 16^a connecting the member 16 to a similar longitudinal member,

not shown, at the opposite side of the frame, uprights 16^b bolted to the inner runner, and other suitably arranged and connected members required for the strength and rigidity 55 of the frame as a whole.

17 represents a vertically movable scraper, which has an oblique front face curved outwardly from its upper to its lower edge, the latter being substantially horizontal. 60 The scraper is obliquely arranged, as shown by Fig. 3, and its forward end extends across the path of the inner runner 12 in advance of the forward end of said runner, the rear end of the scraper being 65 between the two runners.

The scraper is formed and arranged to move snow obliquely from the path of the inner runner 12 toward the outer runner 13. The forward end of the scraper has a vertical edge 17^a (Fig. 5) adapted to move in close proximity to the face of a curb at the inner edge of a gutter. The length of the scraper is preferably considerably less than the distance between the runners, so that the 75 snow displayed by the scraper may accumulate between the runners, although, as hereinafter described, provision is made for the escape of a part of the displaced snow outwardly across the outer runner. 80

I have provided means for varying the height of the scraper, so that its lower edge may work as closely as may be desired to the surface of the gutter. Included in said means is a vertical hanger or connecting 85 rod 19 pivoted at 20 to an ear 21 on the central portion of the upper edge of the scraper, and at 22 to a lever 23 which is fulcrumed at 24 to a fixed upright 26 on the frame, said lever being adapted to swing in 90 a vertical plane and thus raise or lower the scraper 17, through the hanger 19. The lever 23 may be locked in various vertical adjustments by a locking dog 28 carried by the lever and a fixed segmental arm 29 having notches to engage said dog. The arrangement is such that the lower edge of the scraper may be forced below the level of the runners, as shown by Fig. 2, so that the entire forward portion of the structure 100 is slightly lifted and its weight is exerted on the scraper.

The hanger or rod 19 and lever 23 constitute a simple and effective means for vertically adjusting the scraper and causing it to raise the forward portion of the frame, if desired, but do not prevent horizontal displacement and oscillatory movements of the scraper. I have therefore provided for this purpose scraper-bracing means conforming to vertical movements of the scraper and preventing oscillatory movements and horizontal displacement thereof. I have embodied said means in a pair of longitudinally extending struts 31, 32, pivoted at their rear ends upon a transverse pin 33, which is supported by the inner runner 12 and by a bracket 34 attached thereto behind the scraper. The forward ends of said struts are suitably connected as by bolts 35 to the scraper 17, the inner strut 32, which is at the outer side of the runner 12, being connected to the forward end of the scraper, while the outer strut 31, which is offset inwardly from the runner 12, is connected to the central portion of the scraper. The struts swing in vertical planes, and while they conform to vertical adjustments of the scraper, they prevent it from swinging and from being displaced horizontally. The movements of the struts are practically unopposed by friction, so that the struts perform their function without impeding or resisting the vertical adjustments of the scraper. The outer runner 13 and the uprights 14, 15, are made of metal and are preferably integral with each other. The cross section of the metal bar comprising said parts is relatively small or attenuated, so that snow removed by the scraper 17 is free to pass through the opening bounded by said runner and uprights and by the frame member 16.

It will be seen that the scraper is adapted to form, in a gutter, a path or trench that is much narrower than the space between the two runners, one margin of said path being just outside the inner runner and close to a sidewalk curb, and the other margin being between the runners. By thus narrowing the path formed by the scraper the action of the scraper is so concentrated that the plow is enabled to effectively remove hard snow and slush from a gutter close to a sidewalk curb, and leave the removed material between the runners and separated from the curb. The runners are sufficiently spaced apart to afford a wide runner base, and prevent the plow from being top heavy.

37 represents a bar adapted to smoothen or flatten a ridge of snow left by the scraper 17. Said bar, which is technically called a leveler, is pivoted at 38 to a fixed standard 39 on the frame at a point adjacent to and behind the scraper, and extends obliquely

in a direction parallel with the scraper through the above-mentioned opening and 65 across the outer runner 13, as indicated by Fig. 5, the outer portion of the leveler bearing on the rear upright 15. Said upright therefore serves to back the leveler and prevent its rearward displacement. 70

The leveler 37 is adapted to swing in a vertical plane, and is adjustably supported by a hanger 41 pivoted at 42 to the leveler, and a lever 43 fulcrumed at 44 on a fixed upright 45 and pivoted at 46 to the hanger 41. 75

The lever 43 swings in a vertical plane and may be locked at different adjustments by a dog 47 and a fixed notched segment 48. The adjustment of the leveler will depend on the height of the ridge of snow left by the 80 scraper.

The leveler may be a stout wooden bar provided with a wear plate 37^a (Fig. 4) in sliding contact with the upright 15.

Having described my invention, I claim: 85

1. A gutter snow plow comprising a rigid frame including inner and outer runners and a bracket attached to the inner runner and projecting partly across the space between the runners, an oblique scraper having its 90 forward end extended across the forward end of the inner runner and its rear end located between the runners, the scraper being adapted to form a relatively narrow path or trench in a gutter, an inner strut having 95 its rear end pivoted to the inner runner and its forward end attached to the forward end of the scraper, an outer strut having its rear end pivoted to the frame bracket and offset thereby from the inner runner, and its forward end attached to the scraper, and means 100 for raising and lowering the scraper.

2. A gutter snow plow comprising a rigid frame including inner and outer runners, a bracket attached to the inner runner and 105 projecting partly across the space between the runners, and a transverse pin engaged with the inner runner and with said bracket, an oblique scraper adapted to form a relatively narrow path or trench in a gutter, said 110 scraper having its forward end extended across the forward end of the inner runner and its rear end located between the runners, an inner strut pivotally engaged with said pin at its rear end and attached at its forward end to the forward end of the scraper, an outer strut pivotally engaged with said pin at its rear end and spaced by the bracket from the inner runner and attached at its forward end to the scraper, and means for 115 raising and lowering the scraper.

3. A gutter snow plow comprising a rigid frame including inner and outer runners, front and rear uprights on the ends of the outer runner forming parts of the frame, an 125 oblique scraper formed and arranged to

move snow from the path of the inner runner toward the outer runner, an oblique lever pivoted to the frame at a point behind the scraper, and extending obliquely across the outer runner, and vertically adjustable leveler-hanging means adapted to hold the leveler at different inclinations, said leveler bearing against said rear upright and being

supported thereby against backward displacement.

In testimony whereof I have affixed my signature, in presence of two witnesses.
